COMBINED SEAT AND BACK FOR A CHAIR OR THE LIKE

William James Bargen, Waukegan, Ill.

Application March 29, 1950, Serial No. 8,838

Term of patent 14 years

(Cl. D15—8)

To all whom it may concern:

Be it known that I, William James Bargen, a citizen of the United States of America, residing at Waukegan, in the county of Lake and State of Illinois, have invented a new, original, and ornamental Design for a combined Seat and Back for a Chair or the like, of which the following is a specification, reference being had to the accompanying drawing, forming a part thereof.

In the drawing:

Figure 1 is a side elevational view of a combined seat and back for a chair or the like, showing my new design.

I claim:

The ornamental design for a combined seat and back for a chair or the like, as shown.

WILLIAM JAMES BARGEN.
